Glendale, Calif. 91205

Filed Oct. 2, 1967, Ser. No. 8,815

Term of patent 14 years

(Cl. D86—10)

FIG. 1 is a perspective view of a tweezers showing my new design.

FIG. 2 is a side view of same.

FIG. 3 is an enlarged plan view along line 2—2 of FIG. 2 showing the gripping jaw portion of my tweezers design.

FIG. 4 is a fragmentary sectional view taken on line 4—4 of FIG. 3.

FIG. 5 is a sectional view taken on line 3—3 of FIG. 2.

The side opposite to that shown in FIG. 1 is substantially identical to that shown.

I claim:

The ornamental design for tweezers, substantially as shown and described.
